UNITED STATES PATENT OFFICE.

FELIX NORMAN, OF PATTERSON, LOUISIANA.

LOADING-MACHINE.

SPECIFICATION forming part of Letters Patent No. 783,975, dated February 28, 1905.

Application filed April 16, 1904. Serial No. 203,517.

To all whom it may concern:

Be it known that I, FELIX NORMAN, a citizen of the United States, residing at Patterson, in the parish of St. Mary and State of Louisiana, have invented certain new and useful Improvements in Loading-Machines, of which the following is a specification.

The primary object of this invention is to provide a novel apparatus for handling cane 10 when supplying the same to the carrier to be fed to the mill. Obviously the mechanism may be employed in a general way for loading and unloading material and commodities of different kinds.

15 The apparatus embodies a crane or derrick of peculiar formation and actuating means forming an essential part of the apparatus to enable control of the mechanism under all conditions.

20 For a full description of the invention and the merits thereof and also to acquire a knowledge of the details of construction of the means for effecting the result reference is to be had to the following description and drawings hereto attached.

25 While the essential and characteristic features of the invention are susceptible of modification, still the preferred embodiment of the invention is illustrated in the accompanying drawings, in which—

Figure 1 is a side view of a crane or derrick embodying the invention. Fig. 2 is a detail view of the operating mechanism for the several cables. Fig. 3 is a sectional end view of the carriage or trolley and the boom. Fig. 4 is a diagrammatic view in perspective of the turn-table and operating means therefor. Fig. 35 5 is a side view of the upper portion of the derrick, on a larger scale, parts being broken away and portions being in section. Fig. 6

40 is a detail view of the derrick, the king-post being in section, the boom and braces having parts broken away and the actuating means being omitted. Fig. 7 is a side view of the 45 lower portion of the derrick, on a larger scale, showing the operating mechanism in position.

Fig. 8 is a diagrammatic view of the means for operating the carriage or trolley upon the boom. Fig. 9 is a diagrammatic view of the 50 means for raising and lowering the grapple.

Fig. 10 is a diagrammatic view of the means for opening and closing the grapple.

Corresponding and like parts are referred to in the following description and indicated in all the views of the drawings by the same reference characters.

The derrick or crane comprises the king-post 1, boom 2, rear and lateral braces 3, and a plurality of guys for the several parts. The derrick is mounted upon a stationary circular platform 4, so as to be moved to any angular position to conveniently receive the load and deliver the same at the required point of discharge. A collar or sleeve 5 is secured to the upper end of the king-post 1 and has lateral ears, to which the upper ends of the several guys are connected. A bearing-cap 6 receives the upper end of the king-post and is prevented from lateral movement by means of guys 7, leading therefrom and anchored to the ground at a proper distance from the foot of the derrick, so as to brace the structure. The boom 2 is arranged at a point between the upper and lower ends of the king-post and about in the plane of the rear and lateral braces 3 and is stayed by guys 8. A track is pendent from the boom and comprises plate 9 and oppositely-extended flanges at the lower edge of the plate upon which the supporting-wheels 10 of the carriage or trolley 11 are supported. Angle-bars 12 are attached to opposite sides of the plate 9, and their horizontal wings form the flanges or tracks upon which the wheels 10 run. A series of pulleys 13 are arranged near the outer end of the boom, and a corresponding series of pulleys 14 and 15 are located near the inner end of the boom to support the several cables, as will appear more fully hereinafter.

The carriage or trolley 11 may be of any construction and, as shown, is composed of side plates connected in any substantial manner and receiving between them the supporting-wheels 10, sheave-pulleys 16 and 17, and guide-pulleys 18. The carriage is mounted so as to travel the length of the boom and is moved upon the track by means of the cables 19 and 20. The cable 19 is attached to the inner end of the carriage and passes over one of the pulleys 14 and is connected to the drum 10

or windlass 21. The cable 20 is attached to the outer end of the carriage 11 and passes over one of the pulleys 13 and 15 and is likewise attached to the drum 21, the cables 19 and 20 winding in reverse directions upon said drum, so that as one unwinds from the drum the other correspondingly winds upon the drum, thereby preventing any slack in the cables.

10 The grapple is indicated at 22 and may be of any construction and is provided with means to effect an opening and a closing and a raising and a lowering thereof. Sheave-pulleys 23 and 24 are connected to the grapple—the former to effect an opening and a closing of the gripping members and the latter to produce a lifting or a lowering thereof. The operating-cable 25 to cause an opening or a closing of the grapple is connected at one end 15 to the outer portion of the boom and passes around pulleys 17, 23, and 16, thence over pulley 14, and is connected to a drum or windlass 26. The cable 27, by means of which the grapple is raised and lowered, is connected at 20 one end to the king-post, thence around pulleys 16, 24, 17, 13, and 15, and is connected to a windlass or drum 28, forming a part of the actuating mechanism.

When the cable 27 is wound upon the drum 30 28, the grapple is elevated, and when said cable is unwound from the drum the grapple is lowered. The sheave-pulley 23 is connected by ropes or cords 29 with opposite members of the grapple in such a manner that when 35 the sheave-pulley 23 is lowered with reference to the sheave-pulley 24 the grapple opens, and when said sheave-pulley 23 moves upward the jaws or members of the grapple close and retain the cane or other material or commodity 40 to be loaded.

A shed or framework 30 is provided at the foot of the derrick and constitutes a housing for the operating parts—such as the engine, actuating means, and adjunctive parts—said 45 framework being conveniently reached by means of steps 31, attached thereto. The platform 4 is arranged below the framework 30, and its periphery is grooved to receive a rope or cable 32, which is fitted therein and passes 50 over a series of guide-pulleys 33 and has its end portions connected to a drum 34 in such a

manner as to wind in opposite directions thereon. When one end portion of the rope or cable 32 is wound upon the drum 34, the opposite end portion is unwound from said drum, 55 and as a consequence the framework and adjunctive parts are rotated in one direction. A reverse movement of the drum 34 causes the framework to rotate in the opposite direction.

From the foregoing it will be readily understood that the derrick is adapted to be swung about a vertical axis to any angular position and in any adjustment the grapple may be moved to any position within the length of the boom and either opened or closed or raised 60 or lowered, as may be required, by proper manipulation of the several ropes or cables in the manner stated.

Having thus described the invention, what is claimed as new is—

In a loading-machine of the character described, the combination of a stationary circular platform, a derrick mounted upon said platform to swing to any angular position, a bearing and guys for the upper end of the derrick, a framework attached to and rotatable with the derrick, a plate pendent from the boom of the derrick, flanges projected from opposite sides of the plate, a carriage mounted to travel lengthwise of the boom and comprising spaced parts to embrace the said plate and having pulleys mounted upon the aforementioned flanges, cables connected to the carriage for running the same backward and forward, a grapple, a cable for raising and lowering the 80 grapple and having running connection with the carriage, another cable for opening and closing the grapple and having running connection with said carriage, a cable passing around said circular platform to effect rotation 85 of the derrick, a framework mounted upon the derrick, and actuating means supported by means of said framework and having the several cables connected thereto, substantially as set forth.

In testimony whereof I affix my signature in presence of two witnesses.

FELIX NORMAN. [L. S.]
